COMBINED DISPLAY AND STORAGE RACK FOR MAGAZINES OR THE LIKE

Theodore V. Purvin, Riverside, Ill., assignor to Hupp
Corporation, Cleveland, Ohio, a corporation of Vir-
ginia

Filed Nov. 7, 1958, Ser. No. 53,293

Term of patent 14 years

(Cl. D80—9)

FIG. 1

FIG. 2

Fig. 1 is a front perspective view taken from the left side of a combined display and storage rack for magazines or the like showing my new design;

Fig. 2 is a front elevational view thereof, the rear being substantially plain;

Fig. 3 is a right side elevational view thereof; and

Fig. 4 is a fragmentary cross-sectional view thereof taken on line 4-4 of Fig. 2.

The dominant features of my design reside in the full line portions of the drawing.

I claim:

The ornamental design for a combined display and storage rack for magazines or the like, substantially as shown and described.
